UNITED STATES PATENT OFFICE.

GUSTAV TRESENREUTER, OF BERLIN, GERMANY, ASSIGNOR TO THE FIRM OF ARLT AND FRICKE, OF BERLIN, GERMANY.

REGULATING DEVICE FOR GAS OR VAPOR STOVES.

SPECIFICATION forming part of Letters Patent No. 691,019, dated January 14, 1902.

Application filed December 28, 1898. Serial No. 700,497. (No model.)

To all whom it may concern:

Be it known that I, GUSTAV TRESENREUTER, engineer, a subject of the Emperor of Germany, residing at No. 5 Invalidenstrasse, Berlin, N., in the Empire of Germany, have invented certain new and useful Improvements in Regulating Devices for Gas or Vapor Burners, of which the following is a specification.

This invention relates to a device by means 10 of which the gas issuing from gas-burners of all kinds may be exactly regulated. This is effected in accordance with my said invention by making the outlet-opening of pointed conical form which can only be opened or 15 closed gradually by means of a thin pointed part displaceable vertically.

In the accompanying drawings, Figure 1 is a vertical section of one form of the improved regulator. Fig. 2 is a detail view thereof, 20 and Fig. 3 is a vertical section of another form or modification.

In Fig. 1 the outlet *c* is closed by means of a pin *d*, the lower extremity of which forms a sharp point. This pin is guided above by 25 means of a short cylindrical guide-tube *k*, which is capable of vertical displacement within a tube *h*, arranged upon the burner *a*. This displacement is effected by means of an oblique slot *g*, in which the arm *f* works. 30 The extremity *e* of this arm surrounds the pin *d*, while the outer extremity terminates in a knob *f'*. It will readily be understood that by means of this simple arrangement when the knob *f'* is displaced the point *d*' 35 will either leave the aperture *c* or enter the same, as the case may be. According to the extent of the lateral displacement of the arm *f* in the slot *g* the size of the outlet is regulated. In Fig. 1 the aperture is shown completely closed, so that no gas can escape from 40 the burner. In Fig. 2, on the other hand, the aperture *c* is entirely free, so that the full quantity of gas is able to issue. In the intermediate positions of the knob *f'* the size of 45 the aperture varies.

In the burner illustrated in Fig. 1 the tube *h* serves not only for guiding the pin *d* and its cylinder *k*, but also as a cylinder for mixing the gas issuing from the aperture *c* with 50 the air entering through the tube *h* in proximity to the opening of the burner. The mix-

ture of gas and air burns with a blue flame in the known manner. In this form of burner the pin-point *d'* performs a further and very important office—that is to say, it serves also 55 as a cleansing device for the aperture *c*. It is well known that when the gas manufactured from liquid illuminant—such as petroleum, for example—is employed instead of illuminating-gas a fine deposit, which usually 60 consists of a sticky coating, is formed upon the outlet or burner aperture in consequence of the cooling which takes place. This coat may increase to such an extent as to completely close the outlet, and this outlet should 65 consequently be cleansed from time to time. In the present case this cleansing of the burner is effected by means of the point *d'* each time the aperture is closed, owing to the fact that the point *d'* penetrates and removes any coating 70 which may have formed.

The vertical displacement of the pin *d* may also be effected in other ways, Fig. 3. If the tube *k* is prolonged downwardly upon one side and is there provided with a cross-piece 75 *f*, through which a set-screw *i* passes and bears against a projection *i'* from the tube *h*, thus limiting the rise of the pin *d*, the descent of the pin *d* is limited by its encountering the sides of the aperture *c*. Other means for effecting the vertical displacement of the pin *d* 80 may readily be devised.

The form of burner illustrated in Fig. 3 differs from that shown in Figs. 1 and 2 mainly owing to the fact that the closing-pin *d* is replaced by a hollow rod or fine tube. The aperture *c* is thus never completely closed; as even if the point of the pin *d* has entirely entered the conical aperture *c* gas is still able to escape upward through the small 90 tube *d*. This tube or hollow rod forms a pilot-burner. The arrangement is such that the gas issuing at the upper extremity *d''* of the tube *d* is ignited by the flame burning upon the aperture between *h* and *k* at the 95 moment when the supply of gas to the flame proper is interrupted by the descent of the tube *d*. The small flame which is so ignited at the aperture *d''* then serves as an ignition-flame, and it continues to burn until the 100 tube *d* is caused to rise out of the aperture *c*, whereupon the gas naturally follows the most

easy path, which is at the side of the point d' , and becomes ignited above at the ignition or by-pass flame.

I claim—

5 The combination of a burner-head provided with a gas-outlet of conical form, a burner-tube mounted on said burner-head, a guide-tube slidably mounted within the burner-tube, a rod provided with a passage to form a
10 pilot-burner and having a coned end to fit said gas-outlet of the burner-head and at-

tached to said guide-tube, and means for moving said rod and guide-tube to open and close the gas-outlet.

In testimony whereof I have hereunto set my hand, in presence of two subscribing witnesses, this 13th day of December, 1898.

GUSTAV TRESENREUTER.
